UNITED STATES PATENT OFFICE.

JAMES F. BEAN, OF RIO VISTA, CALIFORNIA.

AEROPLANE.

Application filed July 30, 1924. Serial No. 729,102.

To all whom it may concern:

Be it known that I, JAMES FRANKLIN BEAN, a citizen of the United States, residing in the city of Rio Vista, Solano County, 5 and State of California, have invented a new and useful Improvement in an Aero-plane, of which the following is a specification.

My invention relates to improvements in 10 aero-planes wherein a pair of resiliently constructed and mounted wings, composed of overlapping sections arranged to permit a passage of air therethrough during an upward stroke and preventing such passage 15 of air during a downward stroke, operate in conjunction with means for imparting a vertically flapping movement to said wings whereby through successive air pressure and release the aero-plane may be 20 caused to ascend vertically.

The primary object of the present invention is to provide a new and improved aero-plane.

Another object of the invention is to provide 25 a new and improved device of the character described provided with a pair of resilient mechanical wings to which a vertical flapping movement is imparted, to simulate the flying of a bird.

A further object of the present invention 30 is to provide a new and improved aero-plane having a universally mounted propeller arranged to be rotated in a horizontal as well as variously and forwardly inclined 35 planes to assist in the elevation as well as the forward flight of the plane.

A still further object is to provide new 40 and improved means for regulating, adjusting and controlling the degree of vertical flapping movement of the resilient wings whereby the tendency of said wings to elevate the plane vertically may be controlled.

A still further object is to provide a new 45 and improved aero-plane of simple, inexpensive and efficient construction whereby a small plane suitable for individual use may be provided.

Still another object is to provide a new 50 and improved aero-plane capable of greater vertical elevation than present types of aeroplanes whereby an aero-plane may be elevated within a smaller area than is at present possible.

I accomplish these and other objects by 55 means of the improved device disclosed in the drawings forming a part of the pres-

ent specification wherein like characters of reference are used to designate similar parts throughout the said specification and drawings, and in which—

Fig. 1 is a front elevation of my improved aero-plane, partly in section;

Fig. 2 is a broken plan view;

Fig. 3 is a side elevation partly in section;

Fig. 4 is an enlarged broken sectional detail of the overlapping structure of the wings;

Fig. 5 is a broken detail of the means for moving the propeller to different inclinations;

Fig. 6 is an enlarged broken detailed view, partly in section, of one of the units for imparting a vertical flapping movement to the wings; and

Fig. 7 is a front elevation of Fig. 6.

Referring to the drawings the numeral 1 is used to designate an open cigar shaped body frame across the top of which, and arranged transversely thereto are a plurality of resilient members, 2, preferably three in number, which are composed of flexible or resilient material, the purpose of which will hereinafter be more fully set forth.

These members 2 are resiliently connected, in any suitable manner, to the top of the cigar shaped open body frame 1 and are in themselves resilient so that when they are moved out of a normal position there will be a tendency, on account of such resiliency, to return to normal position.

Arranged transversely to the members 2 are a plurality of sections or leaves 3 firmly attached in any suitable manner on their inner edges, that is the side adjacent the body 1, to the members 2, while their other or outer edges are overlapping the next outer adjacent sections on the under sides thereof. These sections 3 are resilient or flexible and normally lie in their overlapping positions in order to present a substantially continuous surface. The effect of this novel arrangement is that when a vertically flapping movement is imparted to the wings constituting the members 2 and sections 3 a passage of air will be permitted through said wings or sections 3 during an upward movement of said wings as the air resistance will press against the upper surface of said sections during an upward movement thereof, and said sections being

resilient will readily move away on their free or outer edges from the adjacent sections 3, as disclosed in dotted lines in Fig. 4 of the drawings, and thereby pass through said wings, while during a downward vertical movement of said wings the air resistance will press the free or outer edges of the sections 3 more firmly against the adjacent sections 3 and thereby effectively close said sections and present a substantially continuous surface and thereby prevent a passage of air through said wings during said downward stroke.

The result of this arrangement is that during a downward stroke of the wings the sections 3 will be pressed against the air and on account of said resistance there will be a tendency on the part of said wings to elevate vertically the aero-plane.

20 A flapping movement is imparted to the wings by means of connecting rods 4 which are in turn connected at their upper ends to suitable bearings 6 connected in turn to one of the members 2. The lower ends of the 25 connecting rods 4 are similarly connected to suitable bearings 7 on wrist pins 8 rigidly mounted upon and projecting from suitable slides 9 slidably mounted within discs 11 which are in turn mounted upon a pair of 30 horizontally disposed shafts 12, one on each side of a depending portion 14 of the body frame 1.

The back of each slide 9 is provided with a rack or teeth 16 which are engaged by the 35 teeth 17 of a sector 18 pivotally mounted upon and rotating with the discs 11, said sector being provided with a bifurcated and slotted lever 19 whose slot slidably engages a pin 21 on a sleeve 22 slidably mounted 40 upon each shaft 12.

Each sleeve 22 is provided with a rotatably mounted collar 23 having diametrically opposed pins 24 engaged by a slotted arm 26 connected to one end of longitudinally disposed rods 27, one on each side of the aero-plane or body 1, the opposite ends of said rods 27 being provided with suitable operating levers 28 arranged to engage a suitable notched sector 29 for holding the wrist pin 50 8 to an adjusted position.

By moving the lever 28 in one direction along the sector 29 the arm 26 will move the sleeve 22 along the shaft 12 which movement of said sleeve 22 will cause the lever 19 of the sector 18 to be actuated and thereby move the slide 9 in a direction which will move the wrist pin 8 thereon nearer the center of the rotating disc 11 and thereby decrease the throw of said wrist pin 8 and consequently a shorter flapping movement to the wings.

As each lever 28 is operable independently of the other it is obvious that the degree of vertical flapping movement of each wing 65 may be controlled and adjusted independ-

ently of the other wing. By means of this novel arrangement by imparting a greater movement to one wing than to the other a greater lifting as well as propulsion will be imparted to one side of the aero-plane than 70 to the other side thereof and the result will be that one side of said aero-plane will move faster than the other thereby providing an effective means for steering the craft during flight. 75

The propulsive effect of the wings is provided by reason of the several resilient or flexible members 2. As the connecting rods 4 are connected to only one of the members 2 in each wing it is obvious that when said connecting rod moves the member to which it is attached in either direction, the entire wing, being resilient and flexible, will follow the movement of the connecting rod 4 in an inclined position with an effect known as 85 sculling, which produces a propulsive effect and has a tendency to drive the aero-plane forward.

A suitable depending frame work 31 carries a motor 32 and a lower frame 33 provided at the front end with suitable wheels 34 and a tailskid 35. A suitable seat 36 is provided to support the pilot.

The inner end of each shaft 12 is provided with suitable bevel gears 37 which mesh with a smaller pinion 38 on a vertically disposed shaft 39 having a beveled pinion 41 on its lower end meshing with a gear 42 driven by the motor 32. On the upper end of the vertical shaft 39 I have provided a universal 100 joint 43 connected in turn to a shorter shaft 44 having a suitable propeller 46 mounted upon its upper end and normally rotating above the wings and body frame in a horizontally disposed plane, the purpose of which 105 will hereinafter be more fully set forth.

The upper shaft 44 is provided with a suitable bearing block 47 provided with lugs 50 which engage an arcuate slot 51 within an arcuate member 52 mounted upon the upper forward portion of the open cigar shaped frame member 1, as disclosed in Figs. 1, 2, and 3 of the drawings.

This bearing block is mounted rigidly upon the upper end of a pair of parallel 115 arms 48 which are pivotally mounted as at 49 upon the top of the body frame 1, as disclosed in Fig. 5 of the drawings. The arms 48 are provided with extensions or arms 53 arranged transversely to the arms 48, said extensions 53 being connected by means of a suitable rod 54 to a bell crank 56 in turn connected by a suitable connecting rod 57 to an operating lever 58.

Normally the propeller is arranged to rotate within a horizontal plane to exert a downward thrust upon the atmosphere. When the propeller 46 is rotating the blast of air produced thereby will of course be directed upon a portion of the upper surface 130

of the wings but as the wings are composed of overlapping sections arranged as previously described, to permit a passage of air downwardly through the planes, it is evident

5 that the air blast produced by said propeller 46 will not tend, by the resulting air pressure, to hold the wings and the aero-plane onto the ground or force it downwardly, but on the contrary, will tend to elevate 10 the aero-plane vertically when operated in conjunction with the flapping movement of the wings as hereinbefore set forth.

By moving the lever 58 along its notched sector 59 the arms 48, whose pivotal point 15 is aligned with the pivotal center of the universal joint 43 on the vertically disposed propeller shaft 39, will move the upper portion 44 of the shaft 39 and the propeller 46 on the top thereof forwardly of the plane 20 and alter the plane of rotation of said propeller 46 from a horizontal plane to a forwardly inclined plane which inclined plane, when the said propeller is rotating, will have a tendency to assist the 25 propulsive effort of the wings, as hereinbefore described, and move the aero-plane forwardly. The aero-plane is provided preferably at the rear end of the body frame 1 thereof, with horizontal and vertical rudder 30 ders 61 and 62, by means of which the course of the aeroplane may be controlled, when in flight, by means of the usual rudder connections, not shown.

In operation the motor rotates the vertically disposed shaft 39 and the propeller 46 to exert a downward thrust and thereby elevate the aero-plane. This downward thrust is further assisted by the flapping movement of the wings which flapping 35 movement is actuated at its greatest capacity during the early stages of elevation of the plane. This flapping will continue, together with the rotation of the propeller 46, until the aero-plane has reached a desired elevation 40 at which time the flapping movement of the wings is decreased by means of the lever 28 until the ascent of the plane is checked.

The lever 58 is then operated to move the 50 propeller 46 into a forwardly inclined plane which will produce a backward thrust of the air blast from said propeller and this backward thrust, in conjunction with the flapping motion of the resilient wings, will 55 tend to move the aero-plane forwardly.

As hereinbefore set forth the aero-plane 60 may be steered by independently adjusting and controlling the degree of movement of either wing so that one wing will flap through a greater arc than the other thereby producing a greater propulsive effort on one side of the aero-plane than on the other which will naturally cause that side to move forwardly at a greater rate of speed than 65 the other side and thereby cause the aero-

plane to travel in a circle, or change its course. This steering effort may be materially assisted by the vertical rudder 62 in the usual manner.

Having thus described my invention what 70 I claim as new and desire to secure by Letters Patent is—

1. An aero-plane comprising a body frame; wings mounted upon each side of the body and resiliently connected thereto and to each other; means for imparting a flapping movement to said wings; means for controlling said last mentioned means for increasing or decreasing the amount of said flapping movement; and a universally mounted propeller 80 mounted above the body and arranged to be held to rotate in a horizontal plane, to elevate said aero-plane vertically, with the assistance of the flapping movement of the wings, and also to be inclined forwardly 85 to assist in moving said aero-plane forwardly.

2. An aero-plane comprising a body frame; resilient wings mounted upon each side of said body and resiliently connected 90 thereto and to each other; means for imparting a vertical flapping movement to said wings; means for controlling the moving means of said wings to increase or decrease the amount of said flapping movement; and a propeller universally mounted above said body and wings and arranged to be rotated in a horizontal plane to assist the wings in elevating the aero-plane vertically and also arranged to be rotated in 100 various planes inclined forwardly of the aero-plane to assist in moving said plane forwardly.

3. An aero-plane comprising an open body frame; resilient wings mounted upon each side of said body and resiliently connected thereto and to each other, said wings being arranged to permit a passage of air therethrough when moving upwardly and to prevent a passage of air when moving downwardly; means for imparting a vertical flapping movement to said wings; means for adjusting and controlling the degree of vertical movement of said flapping motion; a propeller universally mounted above the 115 body and wings and arranged to be rotated in a horizontal plane to assist the wings in elevating said aero-plane vertically, said propeller being also arranged to rotate in variously forwardly inclined planes to move 120 the aero-plane forward.

4. An aero-plane comprising an open body frame; resilient wings mounted upon each side of said body and resiliently connected thereto and to each other, said wings being arranged to permit a passage of air therethrough when moving upwardly and to prevent a passage of air when moving downwardly; means for imparting a vertical flapping movement to said wings; 130

means for adjusting and controlling the degree of vertical movement of said flapping motion; a propeller universally mounted above the body and wings and arranged to be rotated in a horizontal plane to assist the wings in elevating said aero-plane vertically, said propeller being also arranged to rotate in variously forwardly inclined planes to move the aero-plane forward; and means for imparting movement to the propeller and the wing-flapping means.

5. An aero-plane comprising an open cigar-shaped body frame; resilient wings resiliently mounted upon each side of the said body frame and resiliently connected thereto and to each other, said wings comprising overlapping resilient sections arranged to prevent a passage of air therethrough when said wings are moved downwardly and to permit a passage of air when said wings are moved upwardly whereby a flapping movement of said wings will tend, through the medium of air resistance, to elevate said aero-plane; means for imparting vertical movement to said wings; means for adjusting and controlling the degree of vertical flapping of said wings; a propeller universally mounted above the body frame and wings and arranged to rotate in a horizontal plane to assist the flapping of the wings to elevate the aero-plane vertically, said propeller being also arranged to rotate in variously forwardly inclined planes to move said aero-plane forward.

35. An aero-plane comprising an open cigar-shaped body frame; resilient wings resiliently mounted upon each side of the said body frame and resiliently connected thereto and to each other, said wings comprising overlapping resilient sections arranged to prevent a passage of air therethrough when said wings are moved downwardly and to permit a passage of air when said wings are moved upwardly whereby a flapping movement of said wings will tend, through the medium of air resistance, to elevate said aero-plane; means for imparting a vertically flapping movement to said wings; means for adjusting and controlling the degree of vertical flapping of said wings; a propeller universally mounted above the body frame and wings and arranged to rotate in a horizontal plane to assist the flapping of the wings to elevate the aero-plane vertically, said propeller being also arranged to rotate in variously forwardly inclined planes to move said aero-plane forward; and means for imparting movement to the propeller and to the wing flapping means.

60. An aero-plane comprising an open cigar-shaped body frame; resilient wings resiliently mounted upon each side of the body frame and resiliently connected thereto and to each other, said wings comprising laterally disposed resilient overlapping sec-

tions arranged to permit the passage of air through said wings when moved upwardly, and to prevent a passage of air when said wings are moved downwardly whereby a flapping movement of said wings, through the medium of air resistance, will tend to elevate said aero-plane vertically; means for imparting a vertically flapping movement to said wings; means for regulating and controlling the degree of the vertical flapping movement of said wings whereby the tendency to elevate said aero-plane may be regulated and controlled; and a propeller arranged to move the aero-plane forward.

80. An aero-plane comprising an open cigar-shaped body frame; resilient wings resiliently mounted upon each side of the body frame and resiliently connected thereto and to each other, said wings comprising laterally disposed resilient overlapping sections arranged to permit the passage of air through said wings when moved upwardly and to prevent a passage of air when said wings are moved downwardly whereby a flapping movement of said wings, through the medium of air resistance, will tend to elevate said aero-plane vertically; means for imparting a vertically flapping movement to said wings; means for regulating and controlling the degree of the vertical flapping movement of said wings whereby the tendency to elevate said aero-plane may be regulated and controlled; and a propeller arranged to move the aero-plane forward; and means for imparting movement to the wing flapping means and to said propeller.

95. An aero-plane comprising an open cigar shaped body frame; a plurality of resilient members arranged transversely to said body frame and resiliently connected thereto; a plurality of resilient overlapping and transversely disposed sections each secured at one edge thereof to the resilient members and each section having its other edge overlapping the adjacent section on the under side thereof to provide wings arranged to permit a passage of air therethrough during an upward movement and to prevent such passage during a downward movement of said wings; means for imparting a vertical flapping movement to said wings; means for adjusting and controlling the degree of vertical flapping movement of said wings; a propeller universally connected above the frame body and wings and arranged to rotate in various planes to assist in elevating and driving forward the aero-plane.

110. An aero-plane comprising an open cigar shaped body frame; a plurality of resilient members arranged transversely to said body frame and resiliently connected thereto; a plurality of resilient overlapping and transversely disposed sections each secured at one edge thereof to the resilient

- members and each section having its other edge overlapping the adjacent section on the under side thereof to provide wings arranged to permit a passage of air there-through during an upward movement and to prevent such passage during a downward movement of said wings; means for imparting a vertical flapping movement to said wings; means for adjusting and controlling the degree of vertical flapping movement of said wings; a propeller universally connected above the frame body and wings and arranged to rotate in various planes to assist in elevating and driving forward the aero-plane and suitable horizontal and vertical rudder elements pivotally connected to the rear end of the body frame for steering the aero-plane.
- 10 means for adjusting and controlling the degree of vertical flapping movement of said wings; a propeller universally connected above the frame body and wings and arranged to rotate in various planes to assist in elevating and driving forward the aero-plane; and means for imparting movement to the propeller and to the wing moving means.
11. An aero-plane comprising an open cigar shaped body frame; a plurality of resilient members arranged transversely to said body frame and resiliently connected thereto; a plurality of resilient overlapping and transversely disposed sections each secured at one edge thereof to the resilient members and each section having its other edge overlapping the adjacent section on the under side thereof to provide wings arranged to permit a passage of air there-through during an upward movement and to prevent such passage during a downward movement of said wings; means for im-

parting a vertical flapping movement to said wings; means for adjusting and controlling the degree of vertical flapping movement of said wings; a propeller universally connected above the frame body and wings and arranged to rotate in various planes to assist in elevating and driving forward the aero-plane and suitable horizontal and vertical rudder elements pivotally connected to the rear end of the body frame for steering the aero-plane.

12. An aero-plane comprising a body frame; wings mounted upon each side of the body and resiliently connected thereto and each other; means for imparting a flapping movement to said wings; means for controlling said last mentioned means independently for each wing to increase or decrease the amount of movement vertically of each wing whereby a greater vertical flapping movement may be imparted to one wing than to the other whereby a steering effect may be obtained; and a universally mounted propeller arranged to rotate above the body and wings in a horizontal as well as in variously forwardly inclined angles to assist the wings in elevating and propelling forward said aero-plane.

In witness whereof I hereunto set my signature.

JAMES F. BEAN.
